COIN OPERATED TYPEWRITER CONTROL APPARATUS

Jesse B. Graham, San Diego, Calif., assignor of one-half to R. A. Gay, San Diego, Calif.

Application August 1, 1941, Serial No. 405,009

7 Claims. (Cl. 194—1)

My invention relates to a coin operated typewriter control apparatus, more particularly an apparatus for limiting the use of a typewriter over certain periods of time with the insertion of coins therein, and the objects of my invention are:

First, to provide an apparatus of this class with a coin slide which is pressed inwardly with a coin therein and returned for automatically releasing the typewriter keys and starting an escapement timing device;

Second, to provide an apparatus of this class which is not easily tampered with or jammed for using the typewriter without paying therefor;

Third, to provide an apparatus of this class which is readily and easily adjustable for limiting the use of typewriters over various periods of time;

Fourth, to provide an apparatus of this class which is very simple to install, service and operate;

Fifth, to provide an apparatus of this class which is wholly positioned beneath the typewriter in the table on which said typewriter rests;

Sixth, to provide an apparatus of this class which is arranged for use in connection with conventional typewriters without alteration or modification thereof;

Seventh, to provide a novel coin operated typewriter control apparatus of this class; and

Eighth, to provide an apparatus of this class which is very simple and economical of construction, efficient in its action, durable and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a fragmentary plan sectional view taken from the line 1—1 of Fig. 3 showing by dash lines varying positions of some parts and portions of others; Fig. 2 is an enlarged fragmentary sectional view taken from the line 2—2 of Fig. 1 and showing parts in elevation to facilitate the illustration; Fig. 3 is a fragmentary sectional view taken from the line 3—3 of Fig. 4 showing by dash lines different positions of some parts and portions of others and showing a typewriter key control bar with a typewriter key;

Fig. 4 is a fragmentary sectional view taken from the line 4—4 of Fig. 3; Fig. 5 is a sectional view taken from the line 5—5 of Fig. 1 and Fig. 6 is a sectional view taken from the line 6—6 of Fig. 2 showing details of the timing mechanism of my coin operated typewriter control apparatus.

Similar characters of reference refer to similar parts and portions throughout the several views of the drawings:

10 The table top 1, table top side members 2 and 3, Fig. 3, table bottom member 4, table top lock 5, mechanism casing 6, mechanism supporting plate 7, cam supporting arm 8, Fig. 3, cam member 9, cam operated latch 10, trip lever 11, typewriter control levers 12 and 13, lever lock member 14, coin slide engaging member 15, retaining lever 16, springs 17, 18, 19, 20, 21 and 22, coin receiver assembly 23, coin receiver slide 24 and the timing mechanism 25 constitute the principal parts and 20 portions of my coin operated typewriter control apparatus.

The table top 1 is a flat plate-like member having a substantially flat horizontal upper surface 1a on which a typewriter, as indicated by dash lines A is positioned. This typewriter A is secured on the table top 1 by means of the bolts 1b, as shown best in Fig. 3 of the drawings. This table top 1 at its one side edge is provided with a hinge 1c which maintains the table top 1 in 30 hinged connected relation with the table side member 3.

The opposite side edge of the table top 1 is connected with the table top side member 2 by means of the table top lock 5. This lock 5 is a 35 conventional tumbler lock and is provided with a shiftable arm 5a which engages a slotted portion 2a in a metal plate 2b secured in connection with the table top side member 2, all as shown best in Fig. 3 of the drawings.

40 Connected with the table top side members 2 and 3 in opposed relation to the table top 1 is the table bottom member 4 forming an enclosed casing in which the mechanism casing 6 is positioned. This mechanism casing 6 is a rectangular box-like structure in which the mechanism supporting plate 7 is enclosed. As shown in Fig. 4 of the drawings, the top portion 6a of the mechanism casing 6 is provided with a slotted portion 6b therein through which the typewriter control 45 lever 12 extends.

The mechanism supporting plate 7 is a flat member preferably made of sheet metal or the like and this mechanism supporting plate 7 retains the principal operating mechanism of my 55 coin operated typewriter control apparatus.

Secured on the lower side of this mechanism supporting plate 7 is the timing mechanism 25 which consists of substantially conventional clockworks parts. This timing mechanism 25 is provided with a main operating shaft 25a on which the cam supporting arm 8 is rigidly secured by means of the collar 25b and set screws 25c. Secured to the shaft 25a is the inner end of a coiled plate spring 25d which is similar to the main spring of a conventional clockworks and similarly supported. This main spring 25d is arranged to exert force on the shaft 25a on which is secured a disc clutch 25e. This disc clutch 25e is frictionally engaged by the main operating gear 25f which is freely revoluble on the shaft 25a. This main operating gear 25f meshes with a pinion 25g which is in rigid connection with the gear 25h which meshes with the pinion 25j which is rigidly connected with the gear 25k. This gear 25k meshes with the pinion 25m in rigid connected relation with the gear 25n and this gear 25n meshes with a pinion 25p shown by dash lines in Fig. 6 of the drawings. This pinion 25p operates an escapement wheel 25q which is provided with escapement teeth 25r, all as shown best in Fig. 6 of the drawings. The teeth 25r are engaged by the escapement pin 25s which cooperates with the semi-circular in cross section portion 25t of the shaft 25u of the flywheel 25v. This flywheel 25v is operated in one direction by the hairspring 25w. The pin 25x is arranged to limit the movement of the flywheel 25v in one direction. The shaft 25a of the timing mechanism 25 extends upwardly through the mechanism supporting plate 7 on which the cam supporting arm 8 is rigidly mounted, as hereinbefore described. This cam supporting arm 8, as shown in Fig. 1 of the drawings, extends a short distance in one direction from the shaft 25a to the end portion 8a of said cam supporting arm 8. In connection with the cam supporting arm 8 near the end portion 8a thereof is the tension spring 17 which is mounted at its one end on the pin 8b rigidly connected to the cam supporting arm 8. The opposite end of this spring 17 is rigidly connected with the mechanism supporting plate 7 by means of the pin 17a. Secured on the cam supporting arm 8 near the opposite end thereof from the end portion 8a is the cam member 9. This cam member 9 is a circular disc-shaped member, preferably made of metal and is eccentrically mounted on the cam supporting arm 8 by means of the bolt 9a. As shown in Fig. 5 of the drawings, this bolt 9a is provided with a sleeve 9b which extends some distance above the cam member 9 and is engageable with the coin receiving slide 24, as shown by dash lines in Figs. 1 and 5 of the drawings.

Pivotedly mounted on the mechanism supporting plate 7 by means of the pin 10a is the cam operated latch 10. This cam operated latch 10 is provided with an angularly extending portion 10b which is arranged in the path of the cam member 9, as indicated by dash lines in Fig. 1 of the drawings. This cam operated latch 10 is provided with a notch portion 10c which is arranged to retain the pin 11a of the trip lever 11. This cam operated latch 10 is provided with an upwardly extending pin 10d with which is connected one end of the spring 18. This spring 18 is a tension spring and the opposite end thereof from the pin 10d is secured to the pin 18a which extends upwardly from the mechanism supporting plate 7. It will be noted that the

7
tension of the spring 18 tends to force the cam operated latch 10 into engagement with the pin 11a of the trip lever 11, as shown best in Fig. 1 of the drawings.

10
The trip lever 11 is pivotally mounted on the mechanism supporting plate 7 by means of the pin 11b. Connected with this trip lever 11 is a pin 11c on which one end of the tension spring 19 is connected. The opposite end of the tension spring 19 is connected with a pin 19a which extends upwardly from the mechanism supporting plate 7, as shown best in Figs. 1 and 3 of the drawings. As shown in Fig. 4 of the drawings, the trip lever 11 is provided with an offset portion 11d which is arranged to pass over the upper side of the retaining lever 16. It will be further noted that the retaining lever 16 is provided with an offset portion 16a which is arranged to pass over the lever lock member 14 which is positioned against the upper side of the mechanism supporting plate 7, all as shown best in Figs. 3 and 4 of the drawings.

15
20
25
The typewriter control lever 12 is pivotally mounted on a bracket 12a which is secured on the upper side of the mechanism casing 6, as shown best in Figs. 3 and 4 of the drawings. The lower end of this typewriter control lever 12 extends through the slotted opening 7a in the mechanism supporting plate 7, as shown best in Figs. 1 and 3 of the drawings. The lower end of the typewriter control lever 12 is engageable with the lever lock member 14 which is a pivotally mounted member pivotally supported on the pin 14a, as shown best in Fig. 1 of the drawings. The upper end of the typewriter control lever 12 is provided with an angularly disposed edge portion 12b which engages an outwardly extending angular portion 13a of the typewriter control lever 13. This typewriter control lever 13 is pivotally mounted on a pin 13b in connection with a bracket 13c which is secured on the upper side of the table top 1, all as shown best in Figs. 3 and 4 of the drawings.

30
35
40
45
50
55
As shown in Fig. 4 of the drawings, the typewriter control lever 12 extends through a slotted portion 1d in the table top 1 and that the bracket 13d is mounted at one side thereof. Enclosing the bracket 13c and the lower portion of the typewriter control lever 13 is a box-like casing 13d. This casing 13d is provided with a slotted opening in its upper side designated 13e through which the typewriter control lever 13 extends. The upper end portion 13f of the typewriter control lever 13 engages the typewriter key control bar B of the typewriter, as shown by dash lines A in Fig. 3 of the drawings. This typewriter key control bar B is substantially L-shaped in cross section and is arranged to engage the notch portion C' of the typewriter key lever C for locking the typewriter keys in certain position for rendering the typewriter inoperative.

60
65
70
75
80
85
The lever lock member 14 is pivotally mounted on the pin 14a in connection with the mechanism supporting plate 7 and is pivotally mounted over the slotted portion 7a in the mechanism supporting plate 7 as shown best in Fig. 1 of the drawings. This lever lock member 14 is provided with a recess portion 14b which is arranged to engage the typewriter control lever 12 for locking the same in the dash line position D, as shown best in Fig. 1 of the drawings. This lever lock member 14 is provided with an upwardly extending pin 14c with which is connected the tension spring 21 at its one end. The opposite end of this spring 21 is connected to a pin 21a

which extends upwardly from the mechanism supporting plate 7.

In opposed relation to the spring 20, one end of which is connected with the pin 14c and the opposite end of which is connected with the pin 15a of the coin slide engaging member 15. This coin slide engaging member 15 is pivotally mounted on the pin 15b in connection with the mechanism supporting plate 7. This coin slide engaging member 15 is angular in cross section, as shown in Fig. 5 of the drawings and is arranged to be engaged by the coin receiver slide 24 as indicated by dash lines in Fig. 5 of the drawings. This coin slide engaging member 15 is engageable with the retaining lever 16 for shifting the same into the dash line position, as shown in Fig. 1 of the drawings for retaining the typewriter control lever 12 in locked position until the coin receiver slide 24 is returned to the solid line position, as shown in Fig. 1 of the drawings. This retaining lever 16 is pivotally mounted on a pin 16c which is rigidly connected to the mechanism supporting plate 7. The end portion 16b of the retaining lever 16 is engageable with the typewriter control lever 12 near the lower end thereof and the opposite end 16d of this retaining lever 16 is on the same plane as and engageable with the coin slide engaging member 15. This coin engaging member 15 is maintained in engagement with the pin 15c by means of the spring 20. This pin 15c is connected with the mechanism supporting plate 7 and provides a stop for the coin slide engaging member 15.

As shown in Fig. 3 of the drawings, the typewriter control lever 12 is connected with the tension spring 22. This tension spring 22 is secured to a pin 22a which extends from the lower side of the top portion 6a of the mechanism casing 6. This tension spring 22 tends to force the lower end of the typewriter control lever 12 away from the lever lock member 14.

The coin receiver 23 is a conventional coin receiver and selecting device provided with a coin receiver slide 24 which is of the reciprocally mounted type having a coin conveying portion 24a therein, as shown best in Fig. 1 of the drawings. This coin receiver 23 is also provided with a selecting magnet 23a for use in detecting spurious coins of metal subject to magnetic attraction. The outer end portion 24b of the coin receiver slide 24 forms a handle for the manual reciprocal operation thereof when a coin is positioned in the conveyor portion 24a, all as shown best in Fig. 1 of the drawings. This coin receiver 23 is provided with a flange 23b which is secured to the table top side member 2, all as shown best in Fig. 1 of the drawings. As indicated by dash lines in Fig. 5 of the drawings, the coin receiver slide 24 is arranged to engage the coin slide engaging member 15 and the bolt 9a for shifting the cam supporting arm 8, all as indicated by dash lines in Figs. 1 and 5 of the drawings.

The operation of my coin operated typewriter control apparatus is substantially as follows:

When a person desires to use and operate the typewriter, as shown by dash lines A in Fig. 3 of the drawings, he may proceed as follows:

A proper coin must be inserted in the conveyor portion 24a of the coin receiver slide 24. Then the coin receiver slide 24 is pressed inwardly to the limit of its travel, as indicated by dash lines E in Fig. 1 of the drawings. The coin positioned in the conveyor portion 24a is ejected. 70

from the coin receiver 23 and falls into the inner side of the table on the table bottom member 4. As the coin receiver slide 24 passes inwardly to the dash line position E, it engages 5 the coin slide engaging member 15 and pivots the same on the pin 15b to the dash line position, as shown in Fig. 1 of the drawings. This coin slide engaging member 15 forces the retaining lever 16 into the dash line position, as shown in Fig. 1 of the drawings 10 maintaining the lower end of the typewriter control member 12 in the dash line position D which maintains the typewriter key control bar B in the notch portion C' of the typewriter key lever C, all as shown best in Figs. 1 and 3 of the drawings. The coin receiver slide 24 when passing inwardly to the dash line position E also engages the sleeve 9b of the bolt 9a and forces the cam supporting arm 8 to the dash line position F. The end of the cam supporting arm 8 engages the trip lever 11 and forces it to the dash line position G whereby the pin 11a is engaged by the notch portion 10c of the cam operated latch 10 maintaining the trip lever 11 in the solid line position, as shown in Fig. 1 of the drawings. When the cam supporting arm 8 is shifted to the dash line position F, the shaft 25a of the timing mechanism 25 is revolved contracting the plate coil spring 25d and creating a tension thereon which tends to force the shaft 25a 20 to revolve in a counterclockwise direction, as shown in Fig. 1 of the drawings. The spring tension imparted to the shaft 25a by the spring 25d causes the clutch 25e to slowly revolve the gear 25f. The chain of gears 25h, 25k, 25n and 25q, as shown in Fig. 6 of the drawings are operated by the main operating gear 25j as hereinbefore described. The teeth 25r of the escapement gear 25q are engaged by the escapement pin 25s and the semi-circular in cross section portion 25t 30 whereby the cam supporting arm 8 is controlled for slow pivotal movement about the axis of the shaft 25a.

It will be here noted that I prefer to have approximately 30 minutes of time elapse between 45 the passage of the cam supporting arm 8 from the dash line position F to the dash line position H, as shown in Fig. 1 of the drawings. However, this time may be varied by eccentrically shifting the cam 9 on the bolt 9a so that the 50 cam 9 engages the cam operated latch 10 with a shorter or a longer stroke of the cam supporting arm 8 about the axis of the shaft 25a.

It will be here noted that the clutch 25e is 55 revolvably shiftable relatively with the main operating gear 25j but maintains sufficient frictional engagement with the main operating gear 25j to operate the essential clockworks and resist the spring tension thereon of the springs 25d and 17, as shown in Figs. 1, 2 and 6 of the drawings. The plate coil spring 25d operates the cam supporting arm 8 under normal conditions. However, I have provided the tension spring 17 60 in its connected relation with the cam supporting arm 8 for cooperative relation with the spring 25d and the tension of the spring 17 is necessary when the cam 9 engages the end portion 10b of the cam operated latch 10, the tension of the spring 25d being insufficient to operate the cam 9 when shifting the cam operated latch 10 to the dash line position, as shown in Fig. 1 of the drawings.

It will be here noted that when the coin receiver slide 24 is returned to the solid line position by the spring 24c in connection therewith, as shown in Fig. 1 of the drawings, the retaining

lever 16 is released by the coin slide engaging member 15 permitting the typewriter control lever 12 to shift to the solid line position, as shown in Fig. 3 of the drawings, whereby the typewriter key control bar B is released from the typewriter key levers C permitting the normal operation of the typewriter.

When the cam 9 engages the cam operated latch 10 and shifts the same to the dash line position, as shown in Fig. 1 of the drawings, the pin 11a of the trip lever 11 is released from the notch 10c of the cam operated latch 10 and the trip lever 11 is forced into the dash line position J by the spring 19, as shown best in Fig. 1 of the drawings. When this trip lever 11 is forced into the dash line position J, the end portion 11e thereof engages the lower end of the typewriter control lever 12 forcing the same into the dash line position D into the recess 14b of the lever lock member 14 and shifting the typewriter key control lever 13 into the dash line position, as shown in Fig. 3 of the drawings carrying with it the typewriter key control bar B and forcing the typewriter key control bar B into the notches C' of the typewriter key lever C rendering the typewriter inoperative until another coin is inserted into the coin receiver 23, as hereinbefore described. It will be noted that when the coin slide engaging member 15 is forced to the dash line position, as shown in Fig. 1 of the drawings, the tension of the spring 20 forces the lever lock member 14 into the dash line position K, all as shown best in Fig. 1 of the drawings. When this lever lock member 14 is shifted to the dash line position K, the typewriter control lever 12 is released from the recess portion 14b of the lever lock member 14 and the typewriter control lever 12 follows the end portion 16b of the retaining lever 16 when the retaining lever 16 is released by the coin slide engaging member 15 as the coin receiver slide 24 passes backwardly into the solid line position, as shown in Fig. 1 of the drawings.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a coin operated typewriter control apparatus of the class described, the combination of a reciprocally mounted coin receiving slide, a pivotally mounted arm having cam means shiftably mounted in connection therewith near the end thereof and in the path of said coin receiving slide at its one end arranged to shift said arm with the inward movement of said coin receiving slide, a shaft connected with and forming the axis of said arm, escapement timing mechanism in connection with said shaft and operable therewith and spring means in connection with and controlled by said escapement timing mechanism arranged to slowly shift said arm backwardly in predetermined time, said cam means including means for shifting the cam member on said arm.

2. In a coin operated typewriter control apparatus of the class described, the combination of a reciprocally mounted coin receiving slide, a pivotally mounted arm having cam means shiftably mounted in connection therewith near the

end thereof and in the path of said coin receiving slide at its one end arranged to shift said arm with the inward movement of said coin receiving slide, a shaft connected with and forming the axis of said arm, escapement timing mechanism in connection with said shaft and operable therewith and spring means in connection with and controlled by said escapement timing mechanism arranged to slowly shift said arm backwardly in predetermined time, a pivotally mounted cam operated latch extending across the path of said cam means and operable thereby and provided with a notch portion therein, and a pivotally mounted trip lever angularly disposed to said cam operated latch and provided with an extending portion engageable with said notch portion.

3. In a coin operated typewriter control apparatus of the class described, the combination of a reciprocally mounted coin receiving slide, a pivotally mounted arm having cam means shiftably mounted in connection therewith near the end thereof and in the path of said coin receiving slide at its one end arranged to shift said arm with the inward movement of said coin receiving slide, a shaft connected with and forming the axis of said arm, escapement timing mechanism in connection with said shaft and operable therewith and spring means in connection with and controlled by said escapement timing mechanism arranged to slowly shift said arm backwardly in predetermined time, a pivotally mounted cam operated latch extending across the path of said cam means and operable thereby and provided with a notch portion therein, a pivotally mounted trip lever angularly disposed to said cam operated latch and provided with an extending portion engageable with said notch portion, and a spring in connection with said cam operated latch tending to force said notch portion over said extending portion of said trip lever.

4. In a coin operated typewriter control apparatus of the class described, the combination of a reciprocally mounted coin receiving slide, a pivotally mounted arm having cam means shiftably mounted in connection therewith near the end thereof and in the path of said coin receiving slide at its one end arranged to shift said arm with the inward movement of said coin receiving slide, a shaft connected with and forming the axis of said arm, escapement timing mechanism in connection with said shaft and operable therewith and spring means in connection with and controlled by said escapement timing mechanism arranged to slowly shift said arm backwardly in predetermined time, a pivotally mounted cam operated latch extending across the path of said cam means and operable thereby and provided with a notch portion therein, a pivotally mounted trip lever angularly disposed to said cam operated latch and provided with an extending portion engageable with said notch portion, a spring in connection with said cam operated latch tending to force said notch portion over said extending portion of said trip lever, and spring means tending to force said trip lever in transverse opposition to the notch portion of said cam operated latch.

5. In a coin operated typewriter control apparatus of the class described, the combination of a reciprocally mounted coin receiving slide, a pivotally mounted arm having cam means shiftably mounted in connection therewith near the end thereof and in the path of said coin receiving slide at its one end, a shaft connected with and forming the axis of said arm, escapement

timing mechanism in connection with said shaft and spring means in connection with and controlled by said escapement timing mechanism arranged to slowly shift said arm, a pivotally mounted cam operated latch extending across the path of said cam means and operable thereby and provided with a notch portion therein, a pivotally mounted trip lever angularly disposed to said cam operated latch and provided with an extending portion engageable with said notch portion, a spring in connection with said cam operated latch tending to force said notch portion over said extending portion of said trip lever, spring means tending to force said trip lever in transverse opposition to the notch portion of said cam operated latch, and a pivotally mounted typewriter control lever disposed at a right angle to said trip lever and engageable therewith near one end of said typewriter control lever.

6. In a coin operated typewriter control apparatus of the class described, the combination of a reciprocally mounted coin receiving slide, a pivotally mounted arm having cam means shiftably mounted in connection therewith near the end thereof and in the path of said coin receiving slide at its one end, a shaft connected with and forming the axis of said arm, escapement timing mechanism in connection with said shaft and spring means in connection with and controlled by said escapement timing mechanism arranged to slowly shift said arm, a pivotally mounted cam operated latch extending across the path of said cam means and operable thereby and provided with a notch portion therein, a pivotally mounted trip lever angularly disposed to said cam operated latch and provided with an extending portion engageable with said notch portion, a spring in connection with said cam operated latch tending to force said notch portion over said extending portion of said trip lever, spring means tending to force said trip lever in transverse opposition to the notch portion of

said cam operated latch, a pivotally mounted typewriter control lever disposed at a right angle to said trip lever and engageable therewith near one end of said typewriter control lever, and a typewriter table top for supporting a typewriter thereon provided with an opening through which said typewriter control lever extends.

7. In a coin operated typewriter control apparatus of the class described, the combination of 10 a reciprocally mounted coin receiving slide, a pivotally mounted arm having cam means shiftably mounted in connection therewith near the end thereof and in the path of said coin receiving slide at its one end, a shaft connected with 15 and forming the axis of said arm, escapement timing mechanism in connection with said shaft and spring means in connection with and controlled by said escapement timing mechanism arranged to slowly shift said arm, a pivotally mounted cam operated latch extending across the path of said cam means and operable thereby and provided with a notch portion therein, a pivotally mounted trip lever angularly disposed to said cam operated latch and provided with 20 an extending portion engageable with said notch portion, a spring in connection with said cam operated latch tending to force said notch portion over said extending portion of said trip lever, spring means tending to force said trip lever in transverse opposition to the notch portion of said cam operated latch, a pivotally mounted typewriter control lever disposed at a right angle to said trip lever and engageable therewith near one end of said typewriter control lever, a typewriter table top for supporting a typewriter thereon provided with an opening through which said typewriter control lever extends, and a lever lock member in opposed relation to said trip lever provided with a recess 25 portion arranged to receive said typewriter control lever.

JESSE B. GRAHAM.
